UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A WALKING-SKIRT.

SPECIFICATION forming part of Design No. 14,412, dated November 13, 1883.

Application filed August 23, 1883. Term of patent 3½ years.

To all whom it may concern:

Be it known that I, CATHERINE O'HARA, of the city, county, and State of New York, have invented and produced a new and original 5 Design for a Pattern of a Miss's Walking-Skirt, numbered 8,836; and I do hereby declare that the engraved prints accompanying this specification convey to any one accustomed to using paper patterns a clear under- 10 standing of how a garment made up by the pattern will appear.

The design combines a walking-skirt with a deep front drapery draped by plaits and falling in a point at the right side of the front,

and a deep, full back drapery that rounds 15 away from draping plaits in its left-side edge, and falls loosely in a point below draping plaits in its right-side edge.

What I claim as my invention, and desire to secure by Letters Patent, is—

20 The design for a miss's walking-skirt, as shown in the engraved prints accompanying this specification.

CATHERINE O'HARA.
